UNITED STATES PATENT OFFICE.

JOSEPH LAFRANCE, OF MONTREAL, QUEBEC, CANADA, ASSIGNOR OF ONE-HALF TO
ALEXANDRE CHAGNON, OF MONTREAL, QUEBEC, CANADA.

AIR-PUMP.

1,327,833.

Specification of Letters Patent. Patented Jan. 13, 1920.

Application filed March 1, 1919. Serial No. 280,184.

To all whom it may concern:

Be it known that I, JOSEPH LAFRANCE, a British subject, residing at 10 St. Jerome street, in the city of Montreal, in the Province of Quebec, in the Dominion of Canada, have invented certain new and useful Improvements in Air-Pumps; and I do hereby declare that the following is a full, clear, and exact description of the same.

10 The present invention relates to improvements in air-pumps and the main object is to provide a device of the character which is particularly adapted to pump automobile tires; and which will be of simple and cheap 15 construction, compact and powerful.

The invention will be understood with the aid of the accompanying drawings in which:

Figure 1 is a side elevation of the pump 20 attached to an automobile foot board and connected to the tire ready for operation.

Fig. 2 is an enlarged side elevation of the pump, a portion of one cylinder being cut away to illustrate the piston which is in 25 section.

Fig. 3 is a top or plan view of the pump.

Fig. 4 is a side elevation of a modified form of the pump.

Fig. 5 is an enlarged longitudinal section through the modified form of cylinders.

Fig. 6 is a cross section on line A. A. of Fig. 3.

Fig. 7 is a section through the T-coupling illustrating the ball-valve.

35 Like numerals of reference indicate corresponding parts in each figure.

In the drawings, 1 represents a frame or support having at each end thereof a circular member or head 2 suitably threaded 40 and centrally perforated, and 3 is a downwardly projecting member provided at its lower end with a pin 4.

5 and 6 are pipes projecting through the 45 perforated portion in said circular members 2 and having at their outer ends pistons, each of which has secured thereon a cup packing 8. The inner ends of the pipes 5 and 6 are united by a T-coupling 9 in which is provided a valve ball 10. 11 is a lever 50 pivotally mounted at its lower end on the pin 4 and pivotally connected intermediate of its length by the pin 12 to the T-coupling 9. 13 are cylinders suitably threaded at their inner ends to the circular members 2 55 and 14 are heads threaded on the outer ends

of each of said cylinders, each head 14 having an inlet opening which is controlled by a suitable valve 44.

On the upper end of the lever 11 is provided a hand lever 15 which is preferably 60 of suitable length to permit pumping by the driver of the car when seated therein.

The frame 1 may be provided with clamping means to secure the pump to the foot board of an automobile as illustrated in 65 Fig. 1. These clamping means preferably consist of one or more outwardly projecting lugs 16 preferably secured to or made integral with the upper edge of the frame 1, and 17 is an outwardly projecting flange 70 preferably secured on the downwardly projecting member 3 and provided with a threaded hole in which threads a thumb screw 18.

Suitably connected to the T-coupling 9 is 75 an air tube 19 which is adapted to be connected at its outer end to the tire valve.

In the operation of this pump, when the lever 11 is actuated as indicated in dotted lines in Fig. 2, the pistons 7 will be carried 80 to and fro by the pipes 5 and 6, said pipes 5 and 6 communicating with the cylinders 13. It will be clearly understood that as one piston moves outward, *i. e.*, toward the head 14 of its cylinder, it will compress the 85 air in front of it and force the same to pass into the pipe 5 or 6, and thence through the coupling 9 into and through the supply tube 19 to the tire, while at the same time the other piston moves inward toward its 90 cylinder head 2 and draws air into the cylinder through the inlet 44, which automatically opens. The ball 10 located in the T-coupling will be forced against the opposite end of the coupling during the compression stroke of either piston, thus causing the compressed air to enter the air tube 19.

A modification of the invention is illustrated in Figs. 4 and 5. The modification 100 consists in the association with each cylinder 13 of an additional parallel cylinder 20 preferably smaller than the cylinder 13, both cylinders being secured at their outer ends by a head member 21 in which latter 105 there is provided a passage 22 connecting the cylinders and also an inlet valve 44 communicating with cylinder 13. The pistons 7 have cup packings 8 but the pipes 5 and 6 are replaced by a solid rod 23 and 110

24 is a downwardly projecting member preferably secured by any suitable means to the T-coupling 25. 26 and 27 are piston rods each of which projects through a perforated member 28 or head which covers one end of the respective cylinder 20, and 29 is a piston suitably secured to each piston rod and provided with a cup packing 30. The cup packing of this piston 29 is preferably inverted in relation to the packing 8 in the cylinder 13 so as to permit the air to pass between the wall of the cylinder 20 during the out stroke of the piston 29. The piston rods 26 and 27 are longitudinally perforated to form a passage 31 which communicates at its outer ends at 32 with the cylinders 20. An air tube 33 is connected at one end to said T-coupling 25.

In the operation of this pump, when the lever 11 is operated, the pistons 7 and 29 will be moved to and fro simultaneously, the piston 7 during its out-stroke naturally compressing the air in front of it and forcing it through the passage 22 into the cylinder 20, where it is subjected to a further compression by the smaller piston 29 and escapes between the cylinder wall and the packing 30 into the rear portion of the cylinder. During the succeeding in-stroke of the pistons, the air behind the piston 29 is again compressed and forced to escape through the opening 32 into the passage 31 in the piston rod, whence it passes into and through the supply tube 33.

35 What I claim as my invention is:

1. An air pump comprising a frame, two cylinders disposed in longitudinal relation to one another secured to said frame, a piston in each of said cylinders, a piston rod connecting said pistons, said piston rod having an air passage therethrough, an air tube connected to said piston rod, a lever for operating said piston rod, and means on said

frame whereby the pump may be rigidly secured to any convenient part of an automobile or the like; substantially as described. 45

2. An air pump comprising a frame having at each end thereof an outwardly projecting, centrally perforated member, a cylinder secured at each end of said frame to the perforated member, a movable piston in each of said cylinders, a horizontal piston rod passing through each of said centrally perforated members and secured at each end to the adjacent piston, said piston rod being slightly smaller in diameter than the perforation in said members and provided with a central air passage communicating with each of said cylinders, an air tube connected to said piston rod, and a lever fulcrumed on said frame and pivotally connected to said piston rod whereby said piston may be operated simultaneously substantially as described. 55 60

3. An air pump comprising a frame, a main cylinder secured to said frame, a piston rod in alignment with said cylinder, a piston secured to said piston rod adapted to operate in said main cylinder, a secondary cylinder below and in parallel relation to said main cylinder, means connecting said cylinders together, a movable piston in said secondary cylinder, a hollow piston rod secured to the second named piston and communicating with said secondary cylinder, 70 means rigidly connecting said piston rods together, an air tube connected to said hollow piston rod, and means to move said piston rods to and fro; substantially as described. 75 80

Signed at Montreal, Canada, this 30th day of January, 1919.

JOSEPH LAFRANCE.
